FRANK L. O. WADSWORTH, OF PITTSBURGH, PENNSYLVANIA, ASSIGNOR TO THE SPIRELLA COMPANY, OF MEADVILLE, PENNSYLVANIA, A CORPORATION OF PENNSYLVANIA.

METHOD OF MAKING GARMENT-STAYS.

1,250,253.

Specification of Letters Patent. Patented Dec. 18, 1917.

Application filed October 10, 1914. Serial No. 866,081.

To all whom it may concern:

Be it known that I, FRANK L. O. WADSWORTH, a resident of Pittsburgh, in the county of Allegheny and State of Pennsylvania, have invented a new and useful Improvement in Methods of Making Garment-Stays, of which the following is a specification.

This invention relates to the manufacture of wire garment stays and particularly to that form of stay which is made up of wire bent into sinuous form to form two series of loops or eyes lying along the edges of the stay and united by a series of intermediate transverse portions or crossings. In such stays the resistance to flatwise bending is due almost entirely to the torsional stiffness of the transverse portions or crossings, while the resistance to edgewise bending is due almost entirely to the resistance to bending of those portions of the wire which form the edge loops. Usually such stays are subjected to more severe bending stresses in a flatwise direction than they are in an edgewise direction. It is therefore particularly important to form the stays in such a manner that the torsional stiffness and resiliency of the crossing portions of the wire may be as great as possible.

The particular objects of the invention are to provide a method of forming stays of the character described, whereby such stays are not only rendered stiffer in one flatwise direction than in the other but also possess an increased resiliency and increased ability to withstand short bends and avoid taking permanent bends or sets, as compared with stays as heretofore constructed.

According to the present invention the stay is formed in such a manner that each crossing or transverse portion of the wire body is first bent to its final form and position in the completed stay and is then twisted to a sufficient degree to impart a permanent torsional set thereto, the twisting operation being so performed that in the finished stay all of the crossings are twisted or torsionally set in the same direction. As a result of this the resistance to flatwise bending is increased and the stay is particularly stiffened against bending in the direction which produces a twist in the crossings in the same direction as the initial twist; and it is also rendered considerably more elastic and resiliant and therefore capable of being sub-

jected to shorter bends without permanent distortion. As a consequence, a stay manufactured according to this method can be made of smaller and lighter wire than when made according to prior methods, without rendering the stay unduly flexible, as well as producing other advantages which will be readily appreciated by those skilled in the art.

In the accompanying drawings, which represent one suitable embodiment of apparatus for practising my invention, Figure 1 is a front elevation, the left-hand cover plate and the projecting parts on the right and left hand edges of the machine being omitted; Fig. 2 is a detail cross section on the line 2—2, Fig. 1; Fig. 3 is an end elevation of the machine as viewed from the right in Fig. 1; Fig. 4 is a front elevation, partly in section, and showing the driving mechanism and other parts on the right-hand edge omitted from Fig. 1; Fig. 5 is a similar view of the left-hand edge of the machine; Fig. 6 is a partial plan view partly broken out to show a cam; Fig. 7 is an enlarged cross-sectional view on the line 7—7, Fig. 1, and indicating in dotted lines different positions of the spool frame; Fig. 8 is a detail cross-sectional view on the line 8—8, Fig. 4; Figs. 9, 10 and 11 are diagrammatic views showing the various steps of the method; and Fig. 12 is a diagrammatic view, showing a modification of the driving gearing.

In carrying out the method, a wire 1 of suitable size is bent around a series of pins a^1 , a^2 and a^3 , b^1 , b^2 and b^3 , arranged in two rows with the pins of one row staggered or set intermediate with those of the other row, to produce a stay body having two series of oppositely disposed loops 2 lying along the two side edges and united by the transverse portions or crossings 3. The pins of each row may be located sufficiently close together to cause the adjacent loops at each edge of the stay to overlap, as shown in Fig. 9, or they may be spaced so far apart that the loops or eyes remain open, as will be readily understood. Referring to Fig. 9, the wire 1 has just been bent around the pin b^1 to form the transverse portion or crossing 3, lying at an angle to a true transverse line across the stay, and the set of pins a^1 , a^2 and a^3 has been depressed to engage the formed loops. The unformed portion of the wire is now held stationary in any suit-

able manner and the two sets of pins are rotated bodily through 180 degrees around the axis $o-o$, so as to bring the pins and the formed portion of the stay to the position 5 shown in Fig. 10. This imparts a torsional set to the last formed transverse portion or crossing 3 in the direction of the arrow x , Fig. 9. When the twisting movement is wholly completed and the pins and formed 10 portion of the stay reach the position shown in Fig. 10, the unformed portion of the wire is bent around the pin a^1 in the direction indicated by the arrow y . During the last portion of the bending movement the pins 15 b^1 , b^2 and b^3 are withdrawn from engagement with the formed portion of the stay, the wire is drawn tightly about the pin a^1 , and the block carrying the pins a^1 , a^2 and a^3 is moved backwardly to the position shown 20 in full lines; Fig. 11. The pins b^1 , b^2 and b^3 are then advanced to the positions shown in dotted lines at the left of Fig. 11, and are reengaged with the stay fabric. In this position of the parts a new loop or eye and an 25 additional transverse portion or crossing have been formed, and all of the parts are reversed just 180 degrees from the position shown in Fig. 9. The unformed portion of the wire is again held stationary and the 30 pins a^1 , a^2 and a^3 , b^1 , b^2 and b^3 and the stay fabric held thereby are rotated through an angle of 180 degrees around the axis $o-o$, in the same direction as before, thus imparting a twist or torsional set to the newly 35 formed transverse portion or crossing 3^a in the same direction as the twist already imparted to the previously formed crossing 3. This brings the pins and stay fabric to the 40 positions indicated by the dotted lines at the right of Fig. 11 and the unformed portion of the wire is then carried around the pin b^1 in the same direction as before to form a new loop or eye and transverse portion or crossing. During the last portion of 45 this bending movement the pins a^1 , a^2 and a^3 are withdrawn from engagement with the stay and the tension of the wire around the pin b^1 moves the pins b^1 , b^2 and b^3 backwardly or to the position shown in Fig. 9, 50 whereupon the pins a^1 , a^2 and a^3 are advanced and reengaged with the stay fabric. This leaves all of the parts in the same positions which they occupied at the beginning 55 of the cycle and ready for a further complete sequence of movements in the same directions to form a new pair of loops or eyes and transverse portions or crossings.

The method may be carried out by hand, but in the commercial manufacture of the 60 stay according to the method described, a suitably organized machine will be employed, such a machine being shown in the drawings.

The machine illustrated comprises two 65 main operating parts: viz., (1) a segment 5

which supports two pivoted pin-block levers 6 and which rotates in a vertical plane around a horizontal axis to impart the necessary twist to the several transverse or crossing portions of the wire; and (2) a 70 frame 8 which carries a wire supply spool 9 and which rotates about a vertical axis to bend the wire about the pins a^1 , b^1 , etc., in the pin-block levers 6.

Segment 5 comprises two plates 10 which 75 are secured together at a fixed distance from each other and which are provided with peripheral flanges 11 that slide in annular grooves behind a T-shaped rib 12 on the main frame member 13. The outer faces of 80 the plates 10 are in sliding engagement with front and rear cover plates 14 that are bolted or otherwise secured to the main frame 13 and the outer edges of the said plates are provided with gear teeth which are engaged 85 by the gears 15, which are mounted in pairs on short shafts 16 journaled in said cover plates; these shafts being all driven simultaneously in the same direction, by the trains of intermeshing bevel gears on the 90 two vertical shafts 17 and the horizontal shaft 18. The angular length of the toothed edges of the plates 10 is about 120 degrees and the gears 15 are located approximately 95 90 degrees apart, so that during the revolution of the segment 5, the teeth on the plates 10 are always in mesh with one of said pairs of gears; and most of the time with two thereof. The gearing is so proportioned 100 that for every complete rotation of the shaft 18 segment 5 is rotated through exactly 180 degrees.

The pivoted pin-blocks or levers 6 coöperate with an anvil 19 rigidly secured between the plates 10, and are normally held 105 against said anvil by heavy compression springs 20, one for each of said levers; the faces of the operative portions of the pin-blocks being spaced from the anvil members by rollers 21 against which said levers are 110 held by the compression springs. These levers, in addition to having a pivotal movement which permits the pins to be raised and lowered with respect to the anvil, have also a longitudinal or sliding motion with 115 respect thereto, which is permitted by elongated slots 22 in said levers through which the pivot pin 7 passes. The pin-block levers are normally held in their advance positions by light compression springs 23, engaging short arms 24 on the rear ends of 120 said levers.

The spool frame 8 is an upright member journaled at its lower end on a bearing 25 in the main frame and at its upper end secured to a short vertical shaft 26 which is driven through intermeshing bevel gears by a horizontal shaft 27 journaled in the upper portion of the main frame. The driving 125 gears are so proportioned that the spool 130

frame is rotated through exactly 180 degrees for each complete revolution of the driving shaft 27. Rotation of the spool 9 carried by said frame is retarded in any 5 suitable manner, as by a pressure spring 28 bearing against said spool, so as to impart a slight tension to the wire as it is fed to the bending and twisting devices and to take up slack and prevent the wire from getting 10 tangled.

The wire passes from the spool 9 over an idle pulley 29, and thence through a hollow guiding and bending member 30 provided at its outer end with two grooved rollers 31, 15 the grooves in which are of such size as to form a roll pass that hugs the wire closely and has sufficient grip thereon to prevent it from materially twisting. The guiding member 30 is adjustable toward and from 20 the pin-blocks in an opening in the spool frame 8, in order to control the length of the unformed portion of the wire lying between the rollers 31 and the pins a^1 , b^1 , etc.; and it is held in adjusted position in 25 any suitable manner, as by a set-screw 32. It also has one side cut out to receive one end of a pressure rod 33 which slides vertically in an opening in the spool frame and whose upper end projects above the same 30 and is adapted during the rotation of said frame to contact with stationary cams 34 on the main frame. Whenever the pressure rod 33 contacts one of said cams it is forced downwardly against the wire and holds the 35 same tightly. This occurs during the last stage of the bending of the wire around each pin and produces a tension on the wire at this time which coils it tightly around the pin and also pulls the pin-block lever rearwardly to feed the stay through the machine, as more fully hereinafter described. 40 Each of the cover plates 14, of which there are four, is provided with a ribbed lug carrying an idle roller 35. These rollers are 45 located in oppositely disposed pairs on opposite sides of the vertical axis around which the spool frame 8 rotates, and support the inner end of the segment 5 against the lateral pull of the wire on the ends of the pin-blocks 6.

Shafts 18 and 27, which respectively operate the segment 5 and spool frame 8, are driven by the main driving shaft 36, which in turn is driven in any suitable manner, as 50 by an electric motor or a driving pulley thereon (not shown). The driving connections between the main shaft 36 and shafts 18 and 27 are so arranged that said shafts are alternately rotated a complete revolution 55 and always in the same direction. In other words, the driving shaft 18 is rotated one complete revolution and is then stopped, and then the driving shaft 27 begins to rotate and turns through a complete revolution, 60 whereupon it stops and the shaft 18 is again

rotated a complete revolution. To effect this result the main driving shaft 36 is provided with two interrupted gears, a large gear 37 and a smaller gear 38, which respectively operate companion gears 39 and 70 40 located respectively on the shafts 18 and 27. A portion of the circumference of gear 37 is provided with teeth which mesh with the teeth of the gear 39, and the remaining portion of the gear 37 is smooth to cooperate with a smooth concave portion 41 of the gear 39. Whenever the smooth portions of said gears are in engagement with each other gear 37 rotates idly without rotating the gear 39, which in turn is locked against 80 rotation and consequently holds the segment 5 stationary. When the teeth of the gears 37 and 39 are in engagement, the segment 5 is moved around in its circular path. Gears 38 and 40 are of the same construction 85 and arrangement as the gears 37 and 39, but are of different sizes, and the relation between gears 37 and 38 is such that the smooth portion of gear 37 locks the gear 39 at the time when the gear 38 is rotating the 90 gear 40, and likewise the smooth portion of gear 38 locks the gear 40 when the gear 37 is rotating the gear 39.

In the drawings, the parts of the machine have been shown in all views in the positions corresponding to the position of the wire indicated at B, Fig. 10. The spool frame 8 is being rotated in a clockwise direction, Fig. 7, and the segment 5 is held stationary by the smooth parts of the gears 95 37 and 39. The front pin-block lever 6 (which corresponds to the lower pin-block shown in Figs. 10 and 11) carrying the pins b^1 , b^2 and b^3 , is disengaged from the stay fabric and has been moved to its advance 100 37 and 39. The front pin-block lever 6 (which corresponds to the lower pin-block shown in Figs. 10 and 11) carrying the pins b^1 , b^2 and b^3 , is disengaged from the stay fabric and has been moved to its advance 105 37 and 39. The front pin-block lever 6 (which corresponds to the lower pin-block shown in Figs. 10 and 11) carrying the pins b^1 , b^2 and b^3 , is disengaged from the stay fabric and has been moved to its advance 110 37 and 39. The front pin-block lever 6 (which corresponds to the lower pin-block shown in Figs. 10 and 11) carrying the pins b^1 , b^2 and b^3 , is disengaged from the stay fabric and has been moved to its advance 115 37 and 39. The front pin-block lever 6 (which corresponds to the lower pin-block shown in Figs. 10 and 11) carrying the pins b^1 , b^2 and b^3 , is disengaged from the stay fabric and has been moved to its advance 120 37 and 39. The front pin-block lever 6 (which corresponds to the lower pin-block shown in Figs. 10 and 11) carrying the pins b^1 , b^2 and b^3 , is disengaged from the stay fabric and has been moved to its advance 125 37 and 39. The front pin-block lever 6 (which corresponds to the lower pin-block shown in Figs. 10 and 11) carrying the pins b^1 , b^2 and b^3 , is disengaged from the stay fabric and has been moved to its advance 130 37 and 39.

Starting with the various parts of the machine in the positions shown, continuation of the movement of the spool frame carries the wire around in a clockwise direction from position B to position C, Figs. 7 and 10. At position C, or shortly thereafter, the rod 33 engages the cam 34 and the unformed portion of the wire is tightly gripped in the guiding member 30, so that it is tightly drawn around the pin a^1 . The pressure of the wire against said pin forces the rear pin-block lever carrying the same backwardly one half the distance between successive loops along one edge of the stay, or to the position shown in full lines, Fig. 11. At this stage of the movement the other pin-block lever has been lifted out of engagement with the stay fabric and has been carried forward to its advance position, by the action of the cam 42 and spring 23, as described. When the spool carrying frame 8 reaches position D, Figs. 7 and 11, it stops, due to the fact that the smooth portion of the gear 38 engages the smooth concave portion of the gear 40. Simultaneously, the cam 42 passes beyond the roller on the rod 43 and the pressure of the spring 20 upon the elevated pin-block lever pushes back the segment 45 and depresses the pin-block lever, so that the pins b^1 , b^2 and b^3 are reengaged with the stay fabric (as shown in the left-hand portion of Fig. 11). Segment 5 now begins to rotate in a counterclockwise direction,—as shown by the arrow z of Fig. 1—and revolves the stay body about the axis $o-o$ (Figs. 7 and 11). This imparts a twist to the unformed portion of the wire lying between the guiding member 30 and the pin a^1 , including that portion of the wire which has been bent to form the new transverse portion or crossing 3^a and which now lies in its final position. After the segment 5 has rotated through 180 degrees, so as to bring the stay body into the position shown in dotted lines in Fig. 11, the segment becomes stationary and the spool frame 8 begins to rotate in the same direction as before, namely, in a clockwise direction, Fig. 7. The unformed portion of the wire is now bent around the advanced pin b^1 to form a new loop or eye. The spool frame rotates through 180 degrees, and during the last portion of its movement the rod 33 engages a second cam 34, firmly grips the wire and draws it tightly around the pin b^1 . At this time the cam 50 has also depressed the rod 49 and pushed in the segment 45, so that the rear pin-block lever, carrying the pins a^1 , a^2 and a^3 , is disengaged from the stay fabric and advanced one half the distance between adjacent loops or eyes by the rear spring 23. The tension of the wire around the advanced pin b^1 pushes its pin-block lever rearwardly, or to the position shown

in Fig. 9, and at the conclusion of the turning movement of the spool frame 8 the advanced pin-block lever carrying the pins a^1 , a^2 and a^3 , etc., is reengaged with the stay fabric, by the withdrawal of the cam 50 from the roller on the rod 49. The wire then occupies the position, relatively to the several pins, as shown at A in Fig. 9. Spool frame 8 now becomes stationary and the segment 5 again begins to rotate, and in the same direction as before, namely, in a counter-clockwise direction, Fig. 1. This rotates the stay body about the same axis $o-o$ from the position shown in Fig. 9 to the position shown in Fig. 10, which imparts a twist to the unformed portion of the wire, including the last formed crossing portion of the stay body. When the stay body reaches the position shown in Fig. 10 the segment 5 again becomes stationary and the spool frame 8 begins to rotate, as before, bending the unformed portion of the wire around the advanced pin a^1 , through the positions B, C and D, as before, the operations being continued in succession to form the stay body.

The formed stay body travels back along the anvil 19 and around a series of straightening devices, such as the rollers 51, 52, which are journaled between the plates 10 of the segment 5. The intermediate roller 52 preferably has its pivot adjustable in slots 53 in order to increase or diminish the straightening effect. The formed stay passes from the straightening devices to a reel 54 having an axle which engages slots 55 in the edges of the plates 10. Said reel preferably comprises two thin circular plates 56 between which the stay is received, and the edges of which plates are roughened and have a loose contact with the inner face of the T-shaped rib 12, as shown in Fig. 2. This produces a constant drag on the reel whenever the segment 5 is rotating, which winds the formed stay thereon and prevents slack therein.

For clearness of illustration, in the drawings the front pin-block lever is shown in its raised position—with its pins disengaged from the stay fabric—when the spool frame 8 has revolved to the position B (of Figs. 7 and 10), or through only about one third of its complete revolution. Preferably, however, the cam 42 will be made as shown by the dotted line 60, Fig. 6, and so arranged as to disengage the pin-block lever from the stay fabric when the spool frame has reached the position C of Figs. 7 and 10 and has thus completed about two thirds of its movement. This permits the clamping of the stay against anvil 19 by both pin-block levers, through a greater portion of the time occupied in bending the wire around the pins. The arrangement will be such that the pins are disengaged from the

stay fabric just before the forward pin on the pin-block to be disengaged is reached by the wire being bent, said pin-block being advanced and reengaged with the stay fabric as soon as the wire being bent to form the next crossing portion of the stay assumes its final position. The cam 50 will, of course, be similarly arranged. It will also be understood that in the particular machine 10 shown shaft 27 rotates twice for each rotation of the shaft 26, so that the segment 45^a is pushed in twice during each complete rotation of the segment 5, while the segment 45 is pushed in only once. Therefore, one 15 of the strokes of the segment 45^a is an idle stroke which has no effect upon the mechanism.

It will be observed that the stay is formed by relative motion between two members 20 which rotate in planes at 90 degrees from each other, said members rotating alternately and each always rotating in the same direction. This does away entirely with reciprocating action and enables the stay to 25 be formed in a much more simple and direct manner than with prior machines. Each crossing portion of the wire is rotated through substantially 180 degrees so that a very material twist can be imparted thereto, consequently giving greater resistance 30 to bending in one flatwise direction than in the other. In forming the stay, the stay body is held stationary and the wire is bent across the stay to form the edge loops and 35 transverse portions or crossings, and to impart the twist or torsional set to the crossings the unformed portion of the wire is held stationary and the stay body is rotated relatively thereto.

40 In the machine described the spool frame and the segment carrying the pin-blocks are each alternately movable and stationary, or, in other words, each thereof is stationary while the other is at rest and moves while 45 the other is stationary. This, however, is not essential, as the method may be performed on a machine in which both members move all the time but preferably at varying speeds, so that during the operative 50 portion of the movement of each member it moves rapidly and the companion member moves slowly. For example, in Fig. 12 the points 27^a, 18^a and 36^a represent the operating shafts of such a machine, corresponding

to the shafts 27, 18 and 36 of the machine 55 before described. These shafts are connected by pairs of elliptical gears 38^a, 40^a, and 37^a, 39^a, so disposed thereon that when one of the driving gears, say the gear 38^a, is rotating its gear 40^a at the higher speed, 60 the other driving gear 37^a is rotating its gear 39^a at the lower speed, and vice versa. With this or any equivalent arrangement the spool frame will move slowly while the segment is performing its motion to twist 65 the crossings, and the segment will move slowly while the spool frame is rotating to bend the wire.

Various other forms of mechanism are suitable for carrying out the method, that 70 shown being merely illustrative, and it is understood that the invention is not limited to any particular form of mechanism.

What I claim is:—

1. The method of forming wire garment 75 stays, consisting in bending wire to form two series of oppositely disposed edge loops or eyes united by transverse portions or crossings, and after each crossing portion of the wire is bent to final form and before forming the next loop or eye twisting the formed loop or eye to impart a permanent torsional set to the last formed crossing portion of the wire.

2. The method of forming wire garment 85 stays, consisting in holding the unformed portion of the wire and rotating the stay body with relation thereto to impart a twist to the newly formed crossing portion of the wire, and then bending the wire to form a 90 new loop or eye.

3. The method of forming wire garment 95 stays embodying oppositely disposed edge loops or eyes united by transverse portions or crossings, consisting in holding the stay body and bending the wire to form the loops or eyes, and holding the unformed portion of the wire and rotating the stay body relatively thereto to impart a permanent torsional set to the last formed crossing portion of the stay.

In testimony whereof, I have hereunto set my hand.

FRANK L. O. WADSWORTH.
